**BOWLING BALL RETURN MECHANISM WITH
BALL-ACCELERATING AUGER**Robert M. Conklin and Michael G. Gautraud, Muskegon,
Mich., assignors to Brunswick Corporation, a corpora-
tion of DelawareFiled Nov. 13, 1962, Ser. No. 237,026
7 Claims. (Cl. 273—49)

This invention relates to a bowling ball return system and more particularly to the use of a mechanism for conveying a bowling ball from the pit area to a ball return track with acceleration of the ball during engagement by the mechanism.

The elapsed time in which a bowling ball is returned to the bowler is very important in the game of bowling. It is therefore necessary to provide a means for placing the ball on the return track in a minimum of time after the ball enters the pit area and at the same time provide a means which will positively convey the ball to the return track and accelerate it simultaneously without marking the ball.

It is therefore an object of the present invention to provide a new and improved ball return mechanism including a frusto-conically shaped auger having a smaller end adjacent the pit exit and a larger end adjacent the return track to impart acceleration to the ball during engagement with the auger.

Still another object of the present invention is to provide a new and improved bowling ball return mechanism as described in the object hereinabove having lands and grooves thereon, said lands having a varying pitch, with the pitch increasing in a direction toward the return track to give acceleration to a ball while it is engaged by the lands.

A further object of the present invention is to provide a pair of new and improved bowling ball return mechanisms, one in each of adjacent bowling lane pits which will convey balls from each of the adjacent pits to a common ball return track therebetween.

A still further object of the present invention is to provide a pair of rotating augers, one in each of a pair of adjacent bowling lane pits, each auger having a frusto-conical shape and a varying pitch thereon, said pitch increasing in a direction toward a common ball return track therebetween and the pitch of each auger being out of phase with the other so that only one ball at a time will arrive at the return track.

Other objects and advantages will become readily apparent from the following detailed description taken in connection with the accompanying drawings, in which:

FIG. 1 is a plan view of the present invention shown in the pits of a pair of bowling lanes with part of the pit board removed to better show the invention;

FIG. 2 is a sectional elevation taken along line 2—2 of FIG. 1; and

FIG. 3 is a section taken along line 3—3 of FIG. 2.

While an illustrative embodiment of the invention is shown in the drawings and will be described in detail herein, the invention is susceptible of embodiment in many different forms and it should be understood that the present disclosure is to be considered as an exemplification of the principles of the invention and is not intended to limit the invention to the embodiment illustrated. The scope of the invention will be pointed out in the appended claims.

Referring now to the drawings, a ball return mechanism 10 is shown positioned beneath pit 12 at an end of a conventional bowling lane 14. Bowling lane 14 also includes gutters 16 and pin spots 18. Included in pit 12 are pin elevator 20, pit cushion 22 and kickbacks 24. Further, the pit bottom is covered with a pit board 26 sloping

rearwardly and to the center thereof to a ball exit opening 28 located centrally in the pit board 26 as is well known in the art. A ball door 30 is positioned to normally block the opening 28. However, ball door 30 unblocks the ball exit opening 28 when a bowling ball 32 is present. This is accomplished by the rotation of the ball 32, the rotation being imparted thereto by a roller 34 powered by a belt 36 from drive shaft 38. The drive shaft 38 is supported as by bearings 40 and driven by a belt 42 from a shaft 44 which is driven by a belt 46 from motor 48. The rotating ball 32 moves ball door 30 on rollers 31. The door 30 is moved back to its blocking position as by a spring (not shown) after the ball has passed therethrough. The operation of this type ball door is well known in the art and need not be described further herein.

Ball guideway 50 is positioned beneath the ball exit opening 28 so that as the ball 32 passes through the opening, it will be guided by the guideway 50 to the intermediate return track section 52. The entire ball return track is formed with two distinct sections, the intermediate return tracks section 52 and an elongate return track section 53. As shown in FIG. 1, the intermediate ball return track sections 52 from each of a pair of alleys are joined as at 54 to form the elongate common ball return section 53 extending to the bowler's end of the alley (not shown). A guide 56 is positioned to guide the bowling ball 32 as it switches from the intermediate ball return track section 52 to the elongate ball return track section 53.

An auger 58 is operatively related to the intermediate ball return track section 52 as will be described in detail hereinafter. As best shown in FIG. 1, the auger consists of a frusto-conically shaped driving screw having a large and a small end. This driving screw is carried on a shaft 60 generally running from the center of the pit to the elongate ball return track section 53, the shaft being mounted as by a pair of bearings 62. The driving screw also includes lands 64 and grooves 66 running in a counter-clockwise direction from the small end to the large end of the auger. The shaft 60 is powered by a gearing arrangement including gear 68 on shaft 60 which meshes with gear 70 on driven shaft 44, shaft 44 extending substantially the entire width of the pit 12 and supported in bearings at the kickbacks 24 as is well known in the art. The motor 48 drives shaft 44 through belt 46. Thus, the auger 58 is positively driven through the chain of gears, belts and shafts by motor 48.

At the opposite end of the auger, bevel gear 72 meshes with gear 72' attached to shaft 60' supported by bearing 62'. The shaft 60' carries auger 58' positioned in the adjacent pit similarly to auger 58. Thus, the positively driven auger 58 drives auger 58' through this series of bevel gears 72 and 72'.

In operation, the ball 32 is thrown from the bowler's end of the alley (not shown) down the alley 14 and enters the pit 12. The ball is guided by pit cushion 22 and pit floor 26 to the ball exit opening 28. The presence of the bowling ball 32 then causes ball door 30 to open, allowing the bowling ball to pass through ball exit opening 28 as described hereinabove. Bowling ball 32 then engages ball guideway 50 and is guided into contact with both the intermediate ball return track section 52 and the constantly rotating auger 58. The auger 58 is positioned adjacent to the intermediate ball return track section 52 and is spaced less than the diameter of a bowling ball therefrom. It is also substantially parallel to the intermediate ball return track section 52. As the ball 32 engages the constantly rotating auger 58 at the end thereof adjacent the ball guideway 50, it falls into a groove 66 and is guided by the lands 64 along the auger and intermediate ball return track section. The lands 64 are so positioned on auger 58 that the pitch of these lands increases toward

the large end of the auger adjacent ball guide 56, thereby imparting acceleration to the ball 32 as it is supported by the intermediate ball return track section 52. Further, the increase in size of the auger at the end adjacent the ball guide 56 causes the peripheral surfaces of the auger grooves at that end to be rotating faster than peripheral surfaces of the auger at the smaller end adjacent the ball guideway 50. This causes additional acceleration of the ball 32 on the intermediate ball return track section 52.

The ball then engages ball guide 56 and is directed down the elongate common ball return track section 53 to the bowler's end of the alley.

The augers 58 and 58', each positioned similarly in a pair of adjacent alley pits, are mechanically connected as by bevel gears 72 and 72' and one auger has a right hand thread and the other a left hand thread so the balls from each pit will be directed to the elongate common ball return track section 53. Further, these augers are related in an out of phase relationship of 180°, that is, when a groove of an auger from one pit is present at the ball guide 56, a land of the auger from the adjacent pit will be present at the opposite side of the ball guide. This prevents more than one ball at a time arriving at the junction 54 of the intermediate ball return track section 52, and thus prevents ball collisions and malfunctions of the ball return mechanism. This constant out of phase relationship may also be obtained with other forms of connecting means such as: separate synchronized drives on each auger 58, or any mechanical means.

We claim:

1. A ball return mechanism for use with a bowling lane having a ball return track with a ball guideway, an intermediate section and an elongate section, and a pit with a ball exit, comprising: said ball guideway having one end adjacent the ball exit and the other end adjacent the intermediate ball return track section; a rotatable auger adjacent said ball guideway and in operative relation to said intermediate ball return track section, said auger having a frusto-conical shape with a small end and a larger end, the small end adjacent the ball guideway and the large end adjacent the elongate ball return track section so that a ball passing through the ball exit will contact the ball guideway, be guided onto the intermediate ball return track section, and be propelled by the auger therealong to the elongate ball return track section.

2. The mechanism described in claim 1, said auger having lands and grooves to position the ball thereon, with the pitch of said lands increasing toward the larger end.

3. A ball return mechanism for use with a bowling lane having a ball return track with a ball guideway, an intermediate section and an elongate section, and a pit with a ball exit and a pit board, comprising: said ball guideway being disposed beneath said pit board and having one end adjacent the ball exit and the other end adjacent the intermediate ball return track section; a rotatable auger adjacent said intermediate ball return track section and in operative relation substantially parallel thereto, the pitch of said auger increasing in the direction of ball travel from the ball guideway to the elongate ball return track section so that a ball passing through the ball exit will contact the ball guideway, be directed onto the intermediate ball track section and be accelerated by the auger therealong to the elongate ball return track section.

4. A ball return mechanism for use with a bowling

lane having a ball return track and a pit with a ball exit, comprising: a ball support means having one end adjacent the ball exit and the other end adjacent the ball return track; a rotatable auger adjacent said ball support means and substantially parallel to said ball return track and spaced from both the ball support means and the ball return track less than the diameter of a ball so a ball on the ball support means will also engage the rotatable auger, said auger increasing in pitch in the direction of ball travel to accelerate a ball after said ball is transferred from the ball support means to the ball return track.

5. A ball return mechanism for use with a pair of bowling lanes having an elongate common ball return track therebetween and each lane having a pit with a ball return track section, a pit board and a ball exit therein, comprising: a ball guideway in each pit beneath said pit board, said guideway having one end adjacent the ball exit and the other end adjacent the ball return track section; a rotatable auger in each pit adjacent each said ball guideway and in operative relation, substantially parallel to the ball return track section, each auger having a frusto-conical shape with a small end and a larger end, with the pitch of each of said augers increasing toward the larger end, the small end adjacent said ball guideway in each pit and the large end adjacent the elongate common ball return track so that a ball passing through the ball exit in either pit will contact the ball guideway of that pit, be directed onto the ball return track section, and be propelled by the auger therealong to the elongate common ball return track; and means connecting said augers together to effect uniform rotation of the two augers relative to each other.

6. The ball return mechanism as described in claim 5 wherein the last described means comprises meshed gears, one auger thereby driving the other auger, with said augers 180° out of phase so that only one ball at a time can arrive at the common ball return track.

7. A ball return mechanism for use with a pair of bowling lanes, each lane having a pit with a pit board and a ball exit therein, comprising: ball support means in each pit beneath said pit board, having one end adjacent the ball exit; a rotatable auger in each pit adjacent each said ball support means and in operative relation substantially parallel thereto, each auger having a frusto-conical shape with a small end and a larger end, with the pitch of each of said augers increasing toward the larger end, the small end being ahead of the larger end to initially engage a ball traveling along the ball support means so that a ball passing through the ball exit in either pit will contact the ball support means of that pit and be propelled by the auger therealong in a direction away from the ball exit; and meshed gears connecting said augers together to effect uniform rotation of the two augers relative to each other, one auger driving the other auger, with said augers 180° out of phase.
